DESIGN FOR A COOKIE JAR OR SIMILAR ARTICLE

Joseph Burgess Lenhart, Marietta, Ohio, assignor to American Pottery Company, Inc., Marietta, Ohio

Application November 13, 1943, Serial No. 111,689

Term of patent 3½ years

To all whom it may concern:

Be it known that I, Joseph Burgess Lenhart, a citizen of the United States of America, residing in Marietta, county of Washington, and State of Ohio, have invented a new, original, and ornamental Design for a Cookie Jar or Similar Article, of which the following is a specification, reference being had to the accompanying drawing, forming part thereof, wherein:

Figure 1 is a front view of a cookie jar showing my new design on a dark background so as to bring out more clearly the details thereof.

I claim:

The ornamental design for a cookie jar or similar article, substantially as shown and described.

JOSEPH BURGESS LENHART.
